COLLAPSIBLE TUBE

Matthew M. L. Burrell, Millheim, Pa.

Application February 10, 1932. Serial No. 592,139

2 Claims. (Cl. 221—60)

This invention relates to containers of the collapsible tube type in which semi-liquid commodities are placed upon the market and which are utilized to expel the contents, as needed, by compressing one end of the tube. The object of the present invention is to provide a simple and inexpensive discharge nozzle for a collapsible tube which will automatically close when pressure upon the tube is relieved so that the outlet 5 will be sealed and waste of the commodity contained in the tube will be avoided. Another object of the invention is to so construct the delivery end of the tube as to facilitate the application of a cap thereto whereby the delivery nozzle 10 will be protected against opening while the device is in storage or transportation. The invention is illustrated in the accompanying drawing and consists in certain novel features which will be hereinafter first fully described and then 15 more particularly defined in the appended claims.

In the drawing, Fig. 1 is a side elevation of a collapsible tube embodying the invention, a protecting cap being shown in section.

Fig. 2 is a section on the line 2—2 of Fig. 1 with the cap removed.

Fig. 3 is a view, similar to Fig. 2, showing a variation.

The reference numeral 1 indicates a cylindrical tube of soft metal in which paste or a similar commodity is stored in a well-known manner, the tube being closed at one end, as indicated at 2 and as will be understood. The delivery end of the tube is formed with a neck 3 having an annular groove 4 upon its outer circumference and being threaded at its extremity, as will be understood upon reference to Fig. 2. Threaded onto the extremity of the neck 3 is a ferrule or collar 5 the periphery of which is knurled or milled or otherwise fashioned to provide a firm grip for the fingers in placing the collar upon the neck of the tube. The bore of the collar alines with the bore of the neck, as shown clearly in Fig. 2, so that an uninterrupted passage for the escaping material is provided and extending from the outer side of the collar is a spout or nozzle 6 which is formed of some stiff material and is open at one side, as indicated at 7. Secured in the collar 5, and extending therefrom between the side walls of the spout 6, is a resilient plate or leaf spring 8 which, at its free extremity, is curved toward the bottom of the spout 6, as shown at 9, so as to about said bottom and thereby seal the nozzle or spout against escape of the commodity in the tube. The end of the spring is preferably flush with the 55 end of the spout so that there is no projecting

surface to catch and collect dirt at the end of the spring.

When the device is shipped and until it is to be used by the ultimate consumer, a cap 10, which may be of thin rubber, is provided over the nozzle, as shown in Fig. 1, and closely surrounds the same. This cap is of elongated formation so that it conforms to the shape and dimensions of the delivery spout and at its open end is formed with a bead 11 which reinforces the cap and also 60 is adapted to fit snugly within the groove 4 so that the cap will be firmly held to and by the neck of the tube and entirely enclose the spout. When the tube is to be used for a delivery of a portion of its contents, the cap is removed and 65 may be cast aside if the frequent use of the tube is anticipated, but, if the tube is to be used only at rare intervals, the cap may be returned to its position after each use of the tube.

The manner of using the tube will be very 75 readily comprehended. The cap is to be removed and the tube is held in such position that material escaping therefrom will be deposited upon the article to which it is to be applied or by which it is to be employed and the closed end of the tube 80 is then compressed so that the pressure applied thereto will be exerted upon the contained commodity and a portion of the same will be expelled through the delivery spout. As the material flows through the spout, it will overcome the 85 force exerted by the sealing spring 8 so that the spring will be unseated and the material may then escape through the end of the spout, past the end of the spring. When the expelling pressure upon the tube is relieved, the spring will immediately reseat itself under the influence of its 90 own resiliency and will thereby seal the tube so that the material therein will not be wasted and will be protected against the drying influence of the surrounding air. The device is exceedingly 95 simple and inexpensive and is highly efficient for the purpose for which it is designed.

In Fig. 3 is shown a construction in which the spout 20 and the end of the spring 21 are embedded in the neck 22 of the container tube 23, 100 or may be integral therewith. The neck is shorter than in the form shown in Figs. 1 and 2 and has a wider bore, an annular groove 24 being formed externally in the neck immediately back of the end of the neck to receive and hold the 105 elastic band of the cap.

Having thus described the invention, I claim:

1. A container comprising a collapsible tube having a neck, a delivery spout substantially U-shaped in cross section extending from the neck 110

- in alignment therewith, and a resilient sealing spring forming a closure for the open side of the spout and having one end thereof fixed relative to the spout and its other end curved inwardly and the outer edge thereof normally bearing against the back wall of the spout at the outer end thereof whereby the spout will be normally sealed. 80
2. A container consisting of a collapsible tube 10 provided with a neck at its delivery end, said neck having an annular groove in its outer circumference, a delivery spout substantially U- shaped in cross section extending from the neck, a sealing spring forming a closure for the open side of the spout and having one end thereof fixed relative to the spout and its other end curved inwardly and the outer edge thereof normally bearing against the back wall of the spout, and a cap fitted around the spout to completely close the same and provided at its open end with a bead fitting in the annular groove in the neck whereby the cap will be held firmly about the 85 spout. 90
